UNITED STATES PATENT OFFICE

EDWIN G. LITTLE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

DESIGN FOR A HOUSING FOR DUAL CONTROL SWITCH AND LOCK MOVEMENT ASSEMBLY FOR RAILWAYS

Application filed July 22, 1931. Serial No. 40,624. Term of patent 14 years.

To all whom it may concern:

Be it known that I, EDWIN G. LITTLE, a citizen of the United States, residing at Wilkinsburg, in the county of Allegheny and State of Pennsylvania, have invented a new, original, and ornamental design for a Housing for Dual Control Switch and Lock Movement assembly for Railways, of which the following is a specification, reference being had to the accompanying drawings, forming part thereof.

Figure 1 is a top plan view of a housing for dual control switch and lock movement assembly for railways, and,

Figure 2 is a side elevation of said housing for dual control switch and lock movement assembly for railways.

I claim:

The ornamental design for housing for dual control switch and lock movement assembly for railways, as shown.

EDWIN G. LITTLE.
